AUTOMATIC ELECTROMAGNETIC SANDING-GEAR FOR USE ON ELECTRIC RAILWAYS AND TRAMWAYS, &c.

No. 828,717.

Specification of Letters Patent.

Patented Aug. 14, 1906.

Application filed April 3, 1905. Serial No. 253,646.

To all whom it may concern:

Be it known that we, CHARLES WILSON CROSBIE, residing at Sandhill Roarkee, in the Northwest Provinces, India, and ARTHUR WARD, residing at Springfield, Beech Lane, Macclesfield, in the county of Chester, England, subjects of the King of Great Britain and Ireland, have invented new and useful 5 automatic electromagnetic sanding-gear for 10 use on electric railways and tramways operated instantaneously with the electric brake from the controller-handle, of which the following is a specification.

This invention relates to a combination 15 with the sand-valves or sanding-gear as at present in use on electric tramways and rail-ways of a magnetic device that may be either an electromagnet or other device that will exercise a magnetic pull when energized by 20 an electric current.

The object of the said invention is to automatically operate the sand-gear by utilizing 25 the current generated by the motors when acting as generators to energize a solenoid or other magnetic device attached to the sand-gear when the motorman in cases 30 of emergency applies the magnetic, rheostatic, or other types of electric brakes, and thereby minimize the risk of accident by 35 sanding the track instantaneously with the application of the electric or magnetic brakes if the motorman, owing to excitement or other causes, neglects to open the sand-valves in the ordinary manner by the application 40 of the foot to the levers connected therewith.

In the accompanying drawing one method 45 of application of the said invention is illus-trated as applied to a tram-car; but we do not confine ourselves to the precise method 50 shown, as the connections and design of the magnetic device may be varied without de-parting from the nature of our invention.

a is the sand-box.

b is a lever on the rocking shaft, the valve 55 or slide *a'* being connected to one end of said lever and the opposite end of the lever *b* connected to the bell-crank lever *d* by the rod *e*.

f is the pin, which the motorman presses 60 down with his foot when the rails require to be sanded on ordinary occasions.

According to and for the purpose of our invention we connect a solenoid or the ar-mature of an electromagnet, such as *g*, to the

lever *b* by means of a slotted link, as *j*, so as not to affect the ordinary action of the sand- 55 ing-gear. We connect the solenoid or other magnetic device to the motor and controller wiring, so that the current of the motors when working as generators will flow through its windings, the pull of the device increasing 60 in proportion to the current generated. Said solenoid or other electromagnetic device is supported in close proximity to the valve or gear of the sand-boxes, and when the mag- 65 net *g* is energized by the current from the motors acting as generators it draws or pulls the armature *k* to said magnet *g*, which opens the valve *a'* and allows the sand to fall from the sand-boxes through the pipes to the track. One or more tension-springs, such 70 as *l*, can be attached to the valves of the sand-boxes or the lever *b*, as shown, by which said valve is caused to close imme- 75 diately the current is switched off by the controller-handle *m* being moved round to the off position or by the car coming to a stop, when current will not then be generated by the motors. By means of these ten-sion-springs the pull of the device can also 80 be regulated, so that the valves will open at any desired amount of current before skid-ding would take place. A sand box or 85 boxes, a controller, and a solenoid or other electromagnetic device in connection therewith are fitted at each end of the car; but the solenoid or electromagnetic device is only actuated on the same end of the car as the controller operated, which would be the one on the end of the car that would be the front end when running in regular service. 90

By these means the magnetic brake or the rheostatic brake (which is operating the motors as generators through resistances) is able to produce not only a strong retarding effect on the motor-armatures, and conse- 95 quently to the car-wheels through gears, but also at the same time provides increased fric-tion between the car-wheels and the rails, thereby minimizing or preventing skidding, thus bringing the car or vehicle to rest in the shortest possible distance. The combina-tion of controllers used on electric cars for connecting motors in such a way as to propel the cars and by throwing the handle in the other direction, connecting them so that they 100 become generators to retard the cars, is so 105

well known that explanation is not considered necessary.

We claim as our invention—

1. Electromagnetic sanding-gear for use on electric railways, comprising a solenoid connected with the motor and controller wiring, and means connected therewith for opening the sand-valve when the motors are used as generators, in combination with means for operating said sanding-gear independent of the solenoid.
2. Electromagnetic sanding-gear for use on electric railways, comprising a solenoid connected with the motor and controller wiring, means connected therewith for opening the sand-valve when said motors act as gen-

erators for applying the sand direct to the wheels and rails, said valve adapted to be kept open until the car stops.

In testimony whereof we have signed our ²⁰ names to this specification in the presence of two subscribing witnesses.
